TYPE-WRITING MACHINE.

No. 923,016.

Specification of Letters Patent.

Patented May 25, 1909.

Application filed August 25, 1905. Serial No. 275,785.

To all whom it may concern:

Be it known that I, GEORGE C. CARHART, citizen of the United States, and resident of Syracuse, in the county of Onondaga and State of New York, have invented certain new and useful Improvements in Type-Writing Machines, of which the following is a specification.

My invention relates more particularly to platen release mechanisms, and is designed as an improvement on the construction shown in the patent of Alexander T. Brown No. 648,100, dated April 24th, 1900.

The main object of the invention is to simplify in construction and render more effective in operation this type of platen releases.

To the above and other ends, my invention consists in the features of construction and combinations of devices hereinafter fully described and particularly pointed out in the claims.

In the accompanying drawings, Figure 1 is a fragmentary longitudinal sectional view of a platen embodying my invention. Fig. 2 is a view similar to Fig. 1, but showing the parts in somewhat different relations, certain of the parts in the first named figure being omitted and certain of the parts shown in full lines therein being sectioned away. Fig. 3 is a sectional view taken on a plane represented by the line $\alpha-\alpha$ in Fig. 2. Fig. 4 is a view similar to Fig. 3, but showing certain of the parts in different relations. Fig. 5 is a front elevation of the right-hand platen head; and Fig. 6 is a side elevation of the same platen head, viewed from the inside and showing the detent for the platen ratchet wheel added.

In the drawings, the platen is shown as comprising a hollow wooden core 1 and a sheath or outside covering of rubber 2, although said platen may be otherwise constructed. Secured to the right-hand end of the platen by wood screws 3 is a metal friction case or box 4 having an outer flange 5, the periphery of which terminates flush with the rubber sheath of the platen. The right-hand platen head 6 comprises a hub 7, a ratchet wheel portion 8 and a resilient friction ring portion 9. The ratchet wheel portion 8 is provided with side or crown ratchet teeth 10 with which a line space pawl (not shown) is adapted to cooperate and with peripheral teeth 11 with which

engages a detent roller 12 mounted in a lever 13 pivoted at 14 in the platen frame, the other arm of the lever co-acting with a spring 15 which constantly presses the roller 12 into engagement with the peripheral teeth 11 of the ratchet wheel. The resilient friction ring 9 is separated from the remainder of the platen head by a kerf or slit 16 which extends almost entirely around the friction ring, leaving only a narrow neck 17 or portion 17 to connect the latter with the body of the platen head. Thus the friction ring is fixed to or united with the platen head and ratchet wheel. Opposite the connecting portion 17 the friction ring is split 70 or cut away to leave a space 18 between its ends, so that the friction ring is substantially C-shaped.

The friction ring 9 of the platen head 6 enters the friction case 4 and the ratchet portion 8 of said platen head abuts against the face of the flange 5 of said friction case. A portion 8^a is off-set from the ratchet wheel or ring 8 and fits in the friction case near its mouth and between the ratchet ring 8 and the friction ring 9, from which latter the off-set portion 8^a is separated by the kerf 16 and with which it is connected by the portion 17. The portion 8^a of the ratchet ring fits within the mouth of the friction case tightly enough 85 to exclude dust, but the fit is such that the platen when released may turn readily on the platen head, the friction case 4 bearing on the off-set portion 8^a.

A platen axle 19 passes freely through a perforation in the hub 7 of the right-hand platen head and extends through the core of the platen and through a left-hand platen head 20 with which said platen axle is fixedly connected by a pin or screw 21, said platen head being connected with the platen core 1 by wood screws 20^a. The ends of the platen axle are provided with the usual knurled finger wheels 22 and 23.

An operating lever 24 is provided with a pivot pin or stud 25 near its right-hand end, said pin or stud being received in a perforation 26 in the cylindrical hub 7 of the platen head 6. The lever 24 is formed with an arm 27 extending radially outward at its right-hand end and entering the space 18 between the ends of the friction ring 9, the arm 27 being rectangular in cross section. The longer arm of the lever 24 extends inwardly or toward the left and is off-set so as to 110

closely approach the platen axle, the end of the arm being formed with a bevel 28. The beveled end 28 of the operating lever 24 is adapted to contact with a tapered member 5 or cone 29 loosely mounted upon the platen axle 19 so that it may rotate on said platen axle and may also be slid longitudinally of the latter. To the left of the cone 29 a collar 30 is fixed to the platen axle by a screw 31, 10 and confined between the collar 30 and the cone 29 is a wire spring 32 which is coiled around the platen axle and tends constantly to press the cone 29 outwardly or toward the right. 15 A release rod 33 is slidably mounted within the platen axle 19, entering a longitudinal perforation 34 formed in the latter at its right-hand portion. The right-hand end of the release rod terminates exteriorly of the 20 platen wheel 23 and is provided with a finger piece or abutment 35. The release rod 33 is provided near its left-hand end with a cross pin 36 which extends diametrically of the platen axle 19, passing through slots 25 37 in the latter. The ends of the cross pin 36 are positioned to contact with the smaller or right-hand end of the cone 29. The parts having been properly assembled, the bevel 28 at the inner or left-hand end of 30 the operating lever 24 is engaged by the cone 29 and the inner or longer arm of said lever will be forced outwardly or toward the surface of the platen by the pressure of the spring 32 acting through the cone 29. 35 This movement of the longer arm of the lever causes the corners of the rectangular portion 27 of said lever to engage with the ends of the split friction ring 9, expanding the latter against the innate spring tension 40 of its resilient arms, and forcing it in close contact with the inner surface of the friction case 4. It will be observed that the power arm of the operating lever is quite long, extending from the fulcrum 25 of the lever to the bevel 28, while the load arms of said lever are comparatively short, extending from the fulcrum 25 to the corners of the rectangular portion 27. This arrangement 45 enables the lever 24 to exert comparatively great power on the ends of the friction ring 9, causing the latter to frictionally engage or grip the inner face of the friction case 4 with a pressure so great that during the 50 normal operation of the machine the friction ring 9 and the friction case 4 will be forced to move in unison. The parts when in the normal relations just referred to will be in the positions illustrated in Figs. 1, 2 and 3. The friction case 4 is in effect a part or portion of the platen, serving as an inner lining for the latter at the right-hand end. The friction ring or spring ring 9 is integral with the ratchet wheel 8. Consequently 55 when the spring ring and the spring case are in frictional engagement and the ratchet

wheel is turned by the line spacing mechanism, the platen will turn or rotate with said ratchet wheel. The rotary position of the ratchet wheel, and consequently of the platen, is controlled by the spring-pressed 70 detent roller 12 which is in constant engagement with the teeth 11 of the ratchet wheel portion 8 of the right-hand platen head. Consequently, during the regular line spacing operation, the rotary movement 75 of the platen is limited to a distance corresponding to one or more teeth 11 of the ratchet wheel. The platen may be rotated regular line space distances, either by usually employed line space mechanism or by 80 turning either the knob 22 or the knob 23.

When it is desired to rotate the platen variable distances, (by which is meant distances greater or less than the distances determined by the spacing of the ratchet teeth 85 11) for the purpose of writing upon blanks, printed forms, ruled paper or the like, the finger button 35 is pressed inwardly or toward the left, giving a leftward longitudinal movement to the release rod 33 and causing 90 the cross pin 36 at the left-hand end of the latter to slide the cone 29 leftward along the platen axle 19 against the pressure of the spring 32, which is compressed by the operation. The leftward or inward sliding 95 movement of the cone 29 frees the inner or beveled end of the lever 24, and said end is at once swung inward toward the center of the platen by the contractile force of the spring ring 9, the ends whereof tend at once 100 to approach each other and are only stopped when they contact with the surfaces of the longer sides of the part 27 of the lever 24. The parts will now be in the positions represented in Fig. 4 and by the dotted lines in 105 Fig. 2. It will be observed that the spring ring 9, freed from the superior force of the spring 32, has been permitted to contract, so that it now fits loosely within the friction case 4 and so that the frictional connection 110 between the spring case and the spring ring is broken. The result is that if the finger button 35 is held pressed inward or toward the left, and either of the finger wheels 22 or 23 is turned, the platen, because of its 115 connection with said finger wheels through the platen head 20, rivet or screw 21 and platen axle 19, will be turned or rotated a corresponding amount, while the right-hand platen head now disconnected from the 120 platen will be maintained at rest by the detent 12. Consequently the platen may be rotated any desired amount without being restricted in its movements by the line space ratchet wheel and its detent. 125

When the finger button 35 is released, the parts will be returned to the normal positions shown in Figs. 1, 2 and 3, through the force of the spring 32, the spring ring 9, under the influence of the lever 24 being 130

again expanded within the friction case and thereby operatively connecting the right-hand platen head with the platen, by which is meant so connecting the two that said 5 platen head, when it is actuated by the line space pawl will cause the platen to be turned or rotated simultaneously.

The outer ends of the right and left-hand platen heads are closely confined by the side 10 bars or ends of the platen frame (not shown), so that when the frictional engagement between the right-hand platen head and the platen is broken, it is impossible for the right-hand platen head to slip out of its 15 position within the platen, although the two members are separated so that one may turn freely in respect of the other. Or, if preferred, a collar may be fixed on the platen axle, abutting the outer or right-hand end of 20 the hub 7 of the platen head 6.

When the release button 35 is operated, it will be noted that the pressure is toward the left-hand or in the direction of the letter space feeding movement of the platen, so 25 that the longitudinal position of the latter is not altered or disturbed in any wise by the operation of the releasing mechanism.

Various changes in the construction and arrangement of the different parts may be 30 made within the scope of my invention.

What I claim as new and desire to secure by Letters Patent, is:

1. In a typewriting machine, the combination of a platen; a platen head comprising 35 both a ratchet portion and a friction portion; and a lever pivotally connected with said platen head and operative on said friction portion to connect said platen head with said platen.

40 2. In a typewriting machine, the combination of a platen; a friction case fixed thereto; a platen head comprising a ratchet portion without said friction case and a friction ring within said friction case; and a lever pivotally connected with said platen head and operative on said friction ring to expand the latter against said friction case and thereby to operatively connect said platen with said platen head.

45 3. In a typewriting machine, the combination of a platen; a friction case fixed thereto; a platen head comprising a ratchet portion without said friction case and a friction ring within said friction case; a lever pivotally connected with said platen head; a platen axle; and spring pressed means on said platen axle, said means normally acting on said lever to cause the latter to expand said friction ring against said friction case to 60 operatively connect said platen with said platen head.

4. In a typewriting machine, the combination of a platen; a friction case fixed thereto; a platen head comprising a ratchet portion without said friction case and a fric-

tion ring within said friction case; a lever pivotally connected with said platen head; a platen axle; a cone thereon; and a spring normally pressing said cone outwardly so as to cause said lever to expand said friction 70 ring against said friction case and thereby to operatively connect said platen with said platen head.

5. In a typewriting machine, the combination of a platen; a friction case fixed 75 thereto; a platen head comprising a ratchet tooth portion without said friction ring portion within said friction case, and a hub portion; a lever pivoted to said hub and having one of its arms operative on said friction ring, the other and longer of the lever arms extending within the core of the platen; a platen axle passing through the hub portion of the platen head; a cone loosely mounted on said platen axle and operative 80 on the longer arm of said lever; and a collar fixed to said platen axle; a coiled spring surrounding said platen axle between said collar and said cone, said spring operating normally to push said cone outwardly to 85 cause the latter to actuate said lever to expand said friction ring against said friction case and thereby to frictionally connect said platen head with said platen.

6. In a typewriting machine, the combination of a platen; a platen head comprising both a ratchet ring portion and a friction ring portion; a lever pivotally connected with said platen head and operative on said friction ring portion in such wise as 100 to connect said platen head with said platen; and hand operated means adapted to actuate said lever to free said friction ring portion from the control of said lever.

7. In a typewriting machine, the combination of a platen; a friction case fixedly secured thereto; a platen head comprising a ratchet wheel portion outside of said friction case and a friction ring within said friction case; a lever pivotally connected 110 with said platen head and normally operative on said friction ring to expand the latter against the inner surface of said friction case; and hand operated means adapted to 115 actuate said lever to release said friction ring and permit it to contract.

8. In a typewriting machine, the combination of a platen; a friction case fixed thereto; a platen head comprising a ratchet without said friction case and a friction 120 ring within said friction case; a lever pivotally connected with said platen head; a platen axle; spring pressed means on said platen axle normally operative to cause said lever to expand said friction ring against the inner surface of said friction case; and hand operated release means adapted to 125 actuate said lever to free said friction ring and permit it to contract and spring away from the surface of said friction case.

9. In a typewriting machine, the combination of a platen; a platen head comprising a ratchet wheel without said friction case and a friction ring within said friction case; a lever pivoted in said platen head; a platen axle; a cone mounted thereon and normally spring pressed outward against said lever so as to cause the latter to expand said friction ring against the inner surface 10 of said friction case; and a hand operated release rod adapted to move said cone leftward against the pressure of its spring so as to release said lever.
10. In a typewriting machine, the combination of a platen; a friction case fixed thereto; a platen head comprising a ratchet toothed portion without said friction case, a friction ring portion within said friction case, and a hub portion; a lever pivoted to 15 said hub and operative on said friction ring; a platen axle; a cone loosely mounted on said platen axle and operative on said lever; a collar fixed to said platen axle; a coiled spring surrounding said platen axle between 20 said collar and said cone, said spring operating normally to push said cone outwardly to cause the latter to actuate said lever to expand said friction ring against said friction case and thereby to frictionally connect said platen head with said platen; and a release rod extending through a longitudinal perforation in said platen axle and operative to push said cone inwardly 25 against the force of the coiled spring to release said lever and disconnect said platen head from said platen.
11. In a typewriting machine, the combination of a platen; a friction case fixed thereto; a platen head comprising a ratchet toothed portion without said friction case; 30
- 40
- a friction ring portion within said friction case, and a hub portion; a lever pivoted to said hub and operative on said friction ring; a platen axle; a cone loosely mounted on said platen axle and operative on said lever; a collar fixed to said platen axle; a coiled spring surrounding said platen axle between said collar and said cone, said spring operating normally to push said cone outwardly, thereby actuating said lever to expand said friction ring against said friction case and frictionally connecting said platen head with said platen; and a release rod slidably mounted within said platen axle and provided at its outer end with a finger button and at its inner end with a pin operative on said cone to force the latter inwardly, thereby freeing said lever and permitting said friction ring to spring away from the sides of said friction case to release 50 said platen head from said platen.
12. In a typewriting machine, the combination of a platen, a hollow friction case fixed to said platen within the core thereof, a platen head provided with a ratchet and fitting loosely into said friction case, a friction ring or band coöoperative with said friction case and connected with said platen head, a lever operative to expand said friction ring, a platen shaft, means thereon for actuating said lever, and a slide rod within 55 said shaft for operating said means.

Signed at Syracuse, in the county of Onondaga, and State of New York, this 18 day of Aug. A. D. 1905.
